UNITED STATES PATENT OFFICE.

RICHARD EDWARD HALL, OF GRADY, ARKANSAS.

COLTER-CLAMP.

SPECIFICATION forming part of Letters Patent No. 651,352, dated June 12, 1900.

Application filed March 26, 1900. Serial No. 10,271. (No model.)

To all whom it may concern:

Be it known that I, RICHARD EDWARD HALL, a citizen of the United States, residing at Grady, in the county of Lincoln and State 5 of Arkansas, have invented a new and useful Colter-Clamp, of which the following is a specification.

This invention relates to colter-clamps; and its object is to provide a device of this class 10 that can be applied to any plow-beam and securely hold a colter to the same.

The preferred form of the invention is described in the following specification and shown in the accompanying drawings, which 15 form a part of the same, and in which—

Figure 1 is a perspective view of the plow, showing the invention applied thereto. Fig. 2 is an enlarged perspective view of the clamp detached. Fig. 3 is a vertical cross-section 20 of Fig. 1.

Similar numerals of reference designate corresponding parts in all the figures of the drawings.

The invention, as shown, comprises a pair 25 of clips 10 and 11, pivotally connected and adapted to embrace the colter and secure the same to the plow-beam. The clip 10 preferably consists of a single rod, the ends of which are bent at substantially right angles to the 30 main portion to form retaining or bolt arms 12. The ends of these arms 12 are screw-threaded, as at 13, for the reception of the nuts 14. A clamp-plate 15 is provided with suitable openings for the reception of the 35 ends of the retaining or bolt arms 12. The clip 11 is also preferably made of a single rod, and it has its ends bent at substantially right angles to the main portion to form the stop-arms 16. The two clips are pivotally connected at their central portion by means of 40 the pivot-pin 17.

For the purpose of illustrating the applied 45 position of the device an ordinary plow-beam 18 and colter 19 are shown. The clips 10 and 11 are arranged diagonally across the shank of the colter, the retaining-arms 12 of the clip 10 engaging in front of and behind the colter and above and below the plow-beam, respectively, and the clip 11 being arranged in the 50 opposite direction with the stop-arms 16 en-

gaging behind and in front of the colter and above and below the beam, respectively. The threaded ends 13 project beyond the opposite side of the beam and pass through the openings in the clamp-plate 15. The nuts 14 are 55 screwed tightly down upon the plate 15, thereby clamping the colter to the beam. It will be seen that by this simple construction the colter is clamped at four points to the beam, so that there is no chance of its slipping either 60 forward or backward. Furthermore, the colter is clamped by the clip 11 to the beam diagonally across from the front lower portion to the rear upper portion, whereby it is not as liable to be broken or bent as with the ordinary single clip that extends from the rear lower portion to the front upper portion, which thus leaves the front edge of the colter from the top of the beam to the point free.

From the foregoing it is thought that the 70 construction, operation, and many advantages of the herein-described invention will be apparent to those skilled in the art without further description, and it will be understood that the device is not to be limited to clamp- 75 colters only, as it is evident that it may be used for connecting a variety of objects; nor is the invention to be limited to the exact construction shown, as various changes in the size, shape, proportion, and minor de- 80 tails of construction may be resorted to without departing from the spirit or sacrificing any of the advantages of the invention.

Having thus described the invention, what I claim as new, and desire to secure by Letters 85 Patent, is—

1. A clamp of the class described, comprising a pair of crossed clips pivotally connected, substantially as described.

2. A clamp of the class described, comprising a pair of cross-connected clips, one of said clips being provided with bolt ends, substantially as described.

3. A clamp of the class described, comprising a pair of diagonally-crossed clips pivot- 95 ally connected, one of said clips being provided with bolt ends, and a plate connecting the bolt ends, substantially as described.

4. A device of the class described, comprising a pair of clips pivotally connected at their 100

central portions, the ends of said clips being bent at substantially right angles to the main portion, the ends of one arm being screw-threaded forming bolt ends, a retaining-plate connecting said ends, and nuts screwed upon the screw-threaded ends and engaging the retaining-strap, substantially as described.

In testimony that I claim the foregoing as my own I have hereto affixed my signature in the presence of two witnesses.

RICHARD EDWARD HALL.
